UNITED STATES PATENT OFFICE.

BERNARD H. KERSTING, OF BEN AVON, PENNSYLVANIA, ASSIGNOR TO THE DRAVO CONTRACTING COMPANY, OF PITTSBURGH, PENNSYLVANIA, A CORPORATION OF PENNSYLVANIA.

CAPSTAN.

Application filed May 18, 1923. Serial No. 639,782.

To all whom it may concern:

Be it known that I, BERNARD H. KERSTING, a citizen of the United States, residing at Ben Avon, in the county of Allegheny and State of Pennsylvania, have invented a new and useful Improvement in Capstans, of which the following is a full, clear, and exact description.

My invention relates to capstans, and particularly to a capstan having means for applying either hand power or motor power thereto.

I provide means for applying motor power directly to the barrel of a capstan and also provide for the application of hand power either directly or through reducing gearing. I further provide a single connecting element or key which may be placed in different positions for connecting any of these sources of power, as desired. This key is preferably provided with indicating means showing which connection has been made.

There is also provided a series of reversible pawls for the capstan barrel for preventing rotation in either direction, as desired, and a cover is included for preventing engagement of the pawl or pawls when desired.

The connecting element or key is so arranged as to work at a considerable distance from the power shaft, thereby greatly reducing the load on the key and insuring long life in the driving parts.

In the accompanying drawings illustrating the present preferred embodiment of my invention,—

Figure 1 is a vertical section through a capstan embodying my invention and showing a motor power connection in dotted lines.

Figure 2 is a section on the line II—II of Figure 1.

Figure 3 is a half section, partly broken away, on the line III—III of Figure 1.

Figure 4 is a view corresponding to a portion of Figure 1 but showing the key in another position.

Figure 5 is a view similar to Figure 4 but showing the key in its third position.

Figure 6 is a perspective view of the collar employed for operatively connecting the power shaft and the key.

Figure 7 is a perspective view of the connecting key.

Figure 8 is a top plan view of the key in position for hand drive through the gear reduction; and

Figure 9 is a view of the key plate employed for making the other driving connections.

In the illustrated embodiment of the invention, a base 2 is formed integral with a post 3 which supports the capstan barrel 4. The capstan barrel 4 is rotatable on the base 3 and is secured against longitudinal movement by a shoulder 5 at the bottom and by a plate 6 at the top. The plate 6 carries a plurality of planet gears 7 meshing with an internal gear 8 formed in the upper portion of the barrel 4, and also with a sun gear 9 which revolves freely on a central power shaft 10.

The power shaft 10 is driven from any suitable source of power below the deck, as by a worm and worm gear 11, shown in dotted lines in Figure 1. The power shaft 10 revolves in a bushing 12 at the bottom of the post 3, and is free above that point. The top of the shaft 10 is squared, and a collar 13 is carried on the squared portion.

The collar 13 is provided with a keyway 14 adapted to receive a connecting key 15. The collar 13 is held in place by a top plate 16 which has an opening therein adapted to receive the key 15. The key 15 has a shank portion 17 adapted to engage the keyway 14, and an offset toe 18 which may engage either the sun gear 9 or a key plate 19, depending on the particular form of drive desired. As shown in Figure 1, the shank 17 of the key is in engagement with the collar 13 through the keyway 14, while the toe 18 is in engagement with one of a series of keyways 20 formed in the plate 19.

The plate 19 is rigidly secured to the barrel 4, so that with the key placed as shown in Figure 1, the power shaft 10 is directly connected to the barrel and will rotate it at its own speed.

The collar 13 is surrounded by a capstan head 21 having sockets 22 therein for capstan bars when it is desired to operate the capstan by hand.

When the capstan is to be hand driven, the key 15 is lifted up and reinserted in the position of Figure 4. With the key in this position, the shank 17 is clear of the collar 13, while the toe 18 is in engagement with

a keyway 23 formed in the upper portion of the sun gear 9. As the capstan head 21 is turned by hand, the key 15 communicates the hand power to the barrel 4 through the gears 9, 7 and 8, greatly increasing the leverage.

Figure 8 illustrates the top of the key 15 and a portion of the plate 16 when the key is in the position of Figure 4. It will be seen 10 that the key and the plate are both lettered "hand" and "power" for indicating which of the drives is connected to the barrel. The use of a single key with means for indicating the driving connection eliminates any 15 possibility of accidents which might result if a plurality of keys were employed.

The capstan head 21 is further provided with an opening 24 in the side thereof, and the plate 19 is provided with a corresponding keyway 26. If it is desired to connect the capstan head 21 directly to the barrel 4, the key 15 is inserted in the position of Figure 5, so that the shank engages both the capstan head and the key plate 19. It will 25 be noted that when the key is in this position the toe 18 clears both the collar 13 and the keyway 23. When the barrel 4 is driven directly either from the power shaft 10 or by hand from the capstan head 21, the gears 30 idle and the sun gear 9 rotates freely on the shaft 10.

The barrel 4 is provided with one or more pawls 27 which coact with ratchet teeth 28 in the base 2. The ratchet teeth and the 35 pawls are both symmetrical so the pawls may be turned over from the position shown to prevent rotation in the opposite direction. If it is desired to render the pawls inoperative, a pair of semi-annular plates 29 are 40 placed in the groove 30 which contains the ratchet teeth 28, and the pawls slide freely on top of these plates. Figure 2 shows the plates 29 in place, while Figure 3 shows one of them broken away to better illustrate 45 the ratchet teeth 28.

It will be noted that the power shaft is free above the bushing 12, while the barrel is journaled on the post 3. If the capstan is put under a heavy load, the post 3 is free 50 to deflect without bending the shaft 10. Since the power shaft is connected to the barrel through a radially slideable connection, the post 3 may be considerably deflected without interfering in any manner 55 with the power connection and without placing any lateral strain whatsoever on the shaft 10. This makes it possible to design a capstan whose power shaft need only be large enough to withstand the required 60 torque, there being no necessity for greatly increasing the diameter in order to withstand lateral strains.

If the top plate 16 is removed, the collar 13 and the capstan head 21 may be lifted off, 65 exposing the key plate 19. The key plate 19

may in turn be removed, thus giving immediate access to the reduction gearing, and if this in turn is lifted out, the plate 6 and the barrel 4 are immediately removable. Thus the failure of any part need occasion 70 only a minor delay, since the entire capstan may be taken apart without removing the base from its moorings, and new parts may be readily inserted.

I provide a capstan of simple construction 75 and great power flexibility, since either hand or motor power may be applied directly, or hand power may be applied through reduction gearing.

Further, the power shaft is never subjected to lateral strains, and the entire capstan may be readily dismantled. The provision of the single connecting element or key for operating the capstan through any desired power transmission, is of particular 85 value since it completely obviates any danger of motor power being applied, for example, when the hand power is still connected. The provision of the collar 13 on the power shaft positions the key at some 90 distance from the center of the shaft, and greatly reduces the load thereon.

While I have illustrated the preferred form of my invention, it will be understood 95 that it is not limited to such form, but may be otherwise embodied within the scope of the following claims.

I claim:

1. A capstan including a barrel, a power shaft, a capstan bar connection, reducing gears, and a single connecting element for directly connecting the barrel to the power shaft or for connecting the barrel to the capstan bar connection through the reducing gears, as desired, substantially as described. 100

2. A capstan including a barrel, a power shaft, a capstan bar connection, reducing gears, and a single connecting element for directly connecting the barrel to the power shaft, for directly connecting the barrel to the capstan bar connection, or for connecting the barrel to the capstan bar connection through the reducing gears, as desired, substantially as described. 110

3. A capstan including a base having a post, a barrel mounted thereon, a power shaft within the post and journaled therein adjacent the base, the shaft being free above the journal, and a radially slideable power connection above the post between the power shaft and the barrel, substantially as described. 115

4. A capstan including a barrel, a plurality of driving means therefor, the capstan structure having a keyway, and a key adapted to make operative connection between the barrel and one of said driving means when inserted in the keyway in one direction and being adapted to make operative connection between the barrel and 125

another of said driving means when given a different position in said keyway, substantially as described.

5. A capstan including a barrel, a plurality of driving means therefor, the capstan structure having a keyway, a key adapted to make operative connection between the barrel and one of said driving means when inserted in the keyway in one 10 direction and being adapted to make operative connection between the barrel and another of said driving means when given a different position in said keyway, and means for indicating which of said driving 15 means is operatively connected to the barrel, substantially as described.

6. A capstan including a base having a post, a barrel rotatably mounted thereon, a plate removably secured to the post and 20 holding the barrel in place, a power shaft extending through the post, a central gear rotatably mounted on the shaft, a gear mounted on said plate and operatively connecting the central gear and the barrel, a 25 freely rotatable capstan head, and means for operatively connecting the shaft and the central gear, said means also being adapted for operatively connecting the capstan head and the central gear, substantial- 30 ly as described.

7. A capstan including a base having a post, a barrel rotatably mounted thereon, a plate removably secured to the post and holding the barrel in place, a power shaft 35 extending through the post, a central gear rotatably mounted on the shaft, a gear mounted on said plate and operatively connecting the central gear and the barrel, a freely rotatable capstan head, means for 40 operatively connecting the shaft and the central gear, said means also being adapted for operatively connecting the capstan head and the central gear, and means for utilizing said connecting means to directly connect the capstan head and the barrel, sub- 45 stantially as described.

8. A capstan including a barrel, a central power shaft projecting beyond the barrel, a head surrounding the projecting portion of the power shaft, a keyway in the head substantially parallel with the axis of the shaft, a key having a shank portion fitting in the keyway and adapted to engage the power shaft, the key having a toe 50 adapted to engage the barrel to make a direct power connection with the power shaft and the barrel, and reduction gears 55 adapted to engage the barrel to make a direct power connection with the power shaft and the barrel, and reduction gears

connected to the barrel, one of said gears having a keyway adapted to be engaged by the toe of the key when the key is placed in altered position in the keyway, the shank being free of the power shaft when the key is in such altered position whereby the head is operatively connected to the barrel through the reducing gears, substantially 60 65 as described.

9. A capstan including a barrel, a central power shaft projecting beyond the barrel, a head surrounding the projecting portion of the power shaft, a keyway in the head substantially parallel with the axis of the shaft, a key having a shank portion fitting in the keyway and adapted to engage the power shaft, the key having a toe 70 adapted to engage the barrel to make a direct power connection with the power shaft and the barrel, reduction gears connected to the barrel, one of said gears having a keyway adapted to be engaged by the toe of the key when the key is placed in altered 75 position in the keyway, the shank being free of the power shaft when the key is in such altered position whereby the head is operatively connected to the barrel through the reducing gears, and means on the key 80 and on the head for indicating whether the barrel is connected to the power shaft or to the head, substantially as described.

10. A capstan including a barrel, a central power shaft projecting beyond the barrel, a head surrounding the projecting portion of the power shaft, a keyway in the head substantially parallel with the axis of the shaft, a key having a shank portion fitting in the keyway and adapted to engage the power shaft, the key having a toe 90 adapted to engage the barrel to make a direct power connection with the power shaft and the barrel, and reduction gears connected to the barrel, one of said gears having a keyway adapted to be engaged by the toe of the key when the key is placed in altered position in the keyway, the shank being free of the power shaft when the key is in such altered position whereby the head is operatively connected to the barrel through the reducing gears, the barrel and the head having cooperating slots into which the key may be fitted for making a direct connection between the head and the barrel, substantially as described. 95 100 105 110

In testimony whereof I have hereunto set my hand.

BERNARD H. KERSTING.
